UNITED STATES PATENT OFFICE.

PLINY H. FISK, OF NORTH BRANCH, MINNESOTA.

ELECTRIC-SIGNAL DISTRIBUTER.

SPECIFICATION forming part of Letters Patent No. 583,039, dated May 25, 1897.

Application filed October 28, 1895. Serial No. 567,124. (No model.)

To all whom it may concern:

Be it known that I, PLINY H. FISK, a citizen of the United States, residing at North Branch, in the county of Chisago and State of Minnesota, have made certain new and useful Improvements in Electric-Signal Distributers, of which the following is a specification.

The objects of this invention are twofold: first, to actuate, by means of a series of electrical impulses conveyed by a single conducting-wire, a signal or other device at any one of several points or stations connected by such conducting-wire and provided with actuating devices without producing a complete operation of any other actuating device in the series than the one designated, and, second, to produce, by means of a series of electrical impulses sent over a single wire connecting several points or stations, any one of a series of distinct results, such as actuating signals or printing letters or characters simultaneously at one or more of the connected stations, the operator or sender of the impulses being at another of the said connected stations. In the accomplishment of these objects a portion of the mechanism used in transmitting the electrical impulses is converted into a receiving mechanism by the mere reversing of a number of switches. Other sections of the device are used exclusively for transmitting the impulses, and still others are used only in referring the effect of the impulses at the receiving-station to the particular signal or other device to be actuated.

In the accompanying drawings are shown the details of my invention, and in the following specification is described the operations of the several parts and afterward the operation of the mechanism as a whole in producing either of the two general results first mentioned.

In the accompanying drawings, Figure 1 is a partial plan view of the portion of the mechanism used interchangeably in sending or receiving, together with the switches used in converting this section of the device from transmitting to receiving purposes. Figs. 2 and 3 are respectively a side and a rear elevation of the same portion of the mechanism on the cross-sections X X and y y of Fig. 1. Figs. 6 and 7 are respectively a plan view and a side elevation of the sending-keyboard

and other parts of the exclusively-transmitting portion of the device. Fig. 4 shows an enlarged view of the pairs of contact-plates 55 shown in position in Fig. 6. Fig. 8 shows in the lower portion of the sheet a diagrammatical view of the electrical-contact parts of the portion of the device shown in Fig. 1 with their connections and in the upper portion 6c of the sheet a plan view of the exclusively-receiving section of the device, intended to accomplish the latter of the two general results mentioned at the beginning of this specification, the figure as a whole exhibiting the manner in which the effect of a series of electrical impulses may be directed to a specified one of a series of signals or other devices actuated by a respective electromagnet. Fig. 5 shows in elevation a sectional view of Fig. 8 on the 70 cross-line z z. Fig. 9 repeats the diagram of Fig. 8 for the purpose of showing the manner in which the effect of a series of electrical impulses is directed to the first of the two general results intended by the device—viz., that 75 of actuating a designated one of a series of signals or other actuating devices, each located at a separate point or station on a line. It also shows in diagram the operation of the portion of the device used interchangeably 8c in sending and receiving the direction of the local current from battery P', by which this portion of the mechanism is actuated, and of the local current from battery P², by which, in the case of receiving, the effect of the 85 transmitted impulses is carried to the final actuating mechanism, and the relays and switches by means of which the main current is brought into relation with the former of these currents. Fig. 10 shows in a general 90 and more or less diagrammatical way the relation of the mechanism at a sending-station to that at a receiving-station and is designed chiefly to show the changes in adjustment in the interchangeable mechanism, according to 95 its use for sending or receiving purposes.

In detail the device consists of a series of oscillating arms A' A², pivoted by a central shaft A³ and extending horizontally in direction approximately at right angles to each other. Each of the arms A' bears an armature A⁵, which may be actuated by an electromagnet A⁶, the retracting-spring A¹⁴ acting in opposition to the influence of said

electromagnet A⁶. The number of the electromagnets A⁶ in the series varies with the number of signals or devices to be operated, six being, perhaps, the more usual number.

5 To the free end of each arm A' is pivoted a bar F⁴, which is adapted to be actuated in a longitudinal direction by the oscillations of said arm A'.

Two blocks F' F², of insulating material and 10 having deep longitudinal grooves or slots on their lower sides, are mounted one on either side of each bar F⁴ upon metallic supporting-braces D' D² and adapted to glide easily thereon. These blocks are provided with 15 shoulders or projections which are engaged by an adjustable head F³, attached to the bar F⁴, and are thereby drawn forward when the corresponding magnet A⁶ is energized. They are restored to normal position by means of a 20 series of levers II', which are pivoted to standards II², one end being adjustably attached to the next lower bar F⁴ of the series and the other end provided with a head II³, adapted to engage blocks F' F² and drive them backward to normal position when the preceding 25 bar F⁴ is actuated by its corresponding magnet A⁶. The first pair of blocks F' F² are restored to normal position by special electromagnets E' E², acting upon two armatures d' 30 d², connected by yokes d³ d⁴ and pins d⁵ d⁶ to blocks F' F². Each block F² of the series is provided with a contact-brush e⁴, having constant electrical contact in any suitable manner with its corresponding supporting-brace 35 D² and extending downward to contact with a plate e⁵, attached to base A⁴ beneath. When block F² is carried forward by head F³, contact-brush e⁴ is carried forward to a second contact-plate e⁶, adjacent to contact-plate 40 e⁵. To the outward lateral surface of each block F', except the first in the series, are attached two contact-plates e² e³, separated by a pointed projection e' of the body of the insulating-block F', to which they are attached.

On the free end of each arm A² of the series is loosely mounted a block G', of insulating material, carrying a contact-spring G³, which rests normally against plate e³, attached to 50 the next succeeding block F' of the series and just below the insulating projection e' of said block F', being provisionally engaged thereby. The position of block G' is adjusted by means of a nut G² on the end of arm A². In certain 55 cases, as hereinafter described, it may, by reason of its engagement with the projection e' on block F', be carried forward on arm A² when block F' is actuated by its corresponding magnet A⁶. In that case it is restored to its normal 60 position simultaneously with block F' by means of a spring H⁴, attached to said block F'. The free end of each arm A² constitutes a contact-point a', which lies between two contact-plates a² a³, attached to an oscillating block B', of insulating material, pivoted at B² to the base A⁴ or to a standard erected thereon. Frictional springs a⁸ a⁹ rest against and

make contact with plates a³ and a², respectively. Point a' is held normally, by force of retracting-spring A¹⁴, against plate a², which in turn rests against an adjusting contact-screw B³, inserted in and making electrical contact with the next succeeding brace D² of the series. Plate a³ is adjusted by means of a screw a⁷ and should be so placed that the 70 distance normally separating it from the point a' will be considerably less than that traversed by said point a' when it is actuated by magnet A⁶ or the retracting-spring A¹⁴.

To a standard K', made of insulating material, is attached a contact-spring K³, which rests normally against a contact-plate K², also attached to standard K'. A block K¹ is attached to arm F⁴ and adapted, when the latter is actuated, to strike spring K³ and drive it from its contact with plate K². I desire to be understood as not limiting myself to the minutiae of these details in every particular. For instance, if it be found more convenient in construction to combine blocks F' F² in 85 one, or to place the contact-plates e⁵ e⁶ on the upper surface of block F² and attach the contact-brushes e⁴ to the brace D², allowing them to bear on block F² instead of on base A⁴, as shown, or to pivot block B' to the standard 90 at A³ instead of at the remote point shown, or to make use of any of the manifestly-numerous possible vibrations from the method 95 shown of producing the same identical results in a slightly more convenient way, I claim 100 protection in adopting them.

The following electrical connections will be here noticed for the purpose of describing the switches employed in this part of the device: First, a line, consisting of wires t¹⁷ and t⁸, connecting each plate e⁵ with its corresponding magnet A⁶ through contact-plate K² and contact-spring K³, or through switch V⁴ when it is closed, as for purposes herein-after described. Second, a line by wire t¹¹ connecting plate e⁶ with arm A², said arm A² being of conducting material throughout. Third, a line by wire t¹² connecting spring a⁸ with plate e⁵. Fourth, a line by wires t¹³ t¹⁴ connecting spring a⁹ with the next succeeding brace 115 D² of the series. In this line is placed a switch V⁵, which when open breaks the line. Fifth, a provisional path around said switch 120 V⁵ is afforded by wires t³⁶ t³⁶, which in certain cases may be joined electrically at the transmitting-keyboard by the pressure of a key-lever L⁷, bringing a conducting-plate L³⁵ into contact with a pair of conducting-bars L¹³ L¹⁴, to which said wires t³⁶ t³⁶ are attached, as will be hereinafter more fully described in connection with the transmitting-keyboard.

Before proceeding to describe further details it is desirable to show the method of using, both in sending and receiving electrical impulses, the mechanism thus far described, and it will be found that these operations will be most readily understood by considering first those that occur in receiving impulses.

In the case of receiving a series of electrical impulses the arm t^2 of switch V' in the path of the local current generated by battery P' , Figs. 9 and 10, is thrown to plate t^3 , and the 5 current proceeds, by wire t' , switch-arm t^2 , contact-plate t^3 , wire t^4 , to the contact-points of relay R' . Said relay R' is actuated by the main current and serves to produce in the local current the same order of impulses as that 10 occurring in the main current. The local current passes from the armature-lever of relay R' by wires t^5 and t^6 to the arm of switch V^8 , which in receiving is thrown to plate t^{47} , so as to pass the current directly via wire t^{48} 15 to the first supporting-brace D^2 of the series before described.

In receiving impulses switches V^4 and V^5 are closed, as shown in Fig. 10. The current then passes through brace D^2 , contact-brush 20 e^4 , plate e^5 , wire t^{47} , switch V^4 , and wire t^8 to electromagnet A^6 , and thence by wires t^9 t^{10} to battery P' again. This serves to energize magnet A^6 , and thus to actuate arm A' and bar F^4 and all connected parts. Blocks $F' F^2$ 25 will be drawn forward by head F^3 , and the contact-brush e^4 will be drawn forward to rest on plate e^6 . This throws the electrical current forward through wire t^{11} to arm A^2 , thence by contact-point a' , which by the movement 30 of arm A^2 will be now in contact with plate a^3 , through spring a^8 and wire t^{12} to plate e^5 , and from thence by wires t^{47} , switch V^4 , wire t^8 , magnet A^6 , wires t^9 and t^{10} to battery P' , as at first. Thus magnet A^6 will remain energized until a break occurs in the main current, and consequently a break in the local current, which will cause a release of magnet 35 A^6 . Arms $A' A^2$ will then begin to return to normal position under the influence of retarding-spring A^{14} . Point a' will immediately be brought into contact with plate a^2 , and the path of the current will be carried from contact-point a' via plate a^2 , spring a^9 , wire t^{13} , switch V^5 , (closed,) wire t^{14} , the second 40 supporting-brace D^2 of the series, the contact-brush e^4 of the second block F' of the series, and thence to the second magnet A^6 in the manner described in the case of the first magnet A^6 of the series. Thus when the 45 current is again renewed the second magnet A^6 will be energized and not the first, causing a movement of the corresponding arms $A' A^2$ and blocks $F' F^2$. If this renewal of the current be instantaneous, block F' of the 50 second magnet A^6 in the series will be drawn forward before spring G^3 of the first magnet A^6 reaches its normal position in contact with plate e^3 of said second block F' and spring G^3 will fall on plate e^2 of said second block F' ; 55 but if the break in the current be protracted the spring G^3 will reach plate e^3 before the latter is actuated and will remain in contact therewith, being carried forward by means of its engagement with projection e' on the 60 second block F' , as before described. The same order of movements will be repeated 65

until each of the magnets A^6 in the series has been energized, and as a result each spring G^3 of the series will rest finally in contact with either plate e^2 or e^3 of the next 70 succeeding block F' , according as the intervals between the energizing of the two successive magnets A^6 involving those parts have been short or long. From the final plate C^6 of the series the current from battery P' is 75 carried by wire t^{50} , plate d^{11} , brush d^7 , wire t^{21} to magnet E' , and from thence it proceeds by wire t^{22} to battery P' again. This energizes magnet E' and causes a restoration of the first block F' to its normal position, the 80 current through said magnet E' being finally broken by the withdrawing of brush d^7 from plate $2''$ in connection with the movement of yoke d^2 , as before described.

The final effects produced at the receiving- 85 station by the various combinations of the springs G^3 with the plates e^2 and e^3 will be explained hereinafter. The use of this portion of the mechanism in sending impulses is as follows: First, the arm of switch V^2 is 90 thrown to plate t^7 , so as to cause the main current to pass through the contact-points of relay R^2 . The arm of switch V' is thrown to plate t' , so as to carry the local current from battery P' through relay-magnet R^2 and exclude it from the contact-points of relay R' . This, in effect, reverses the relation of the local current to the main current from that which they hold in receiving and causes the "makes" and "breaks" in the former to be 95 transmitted to the latter. Furthermore, the arm of switch V^8 , Fig. 9, is thrown to plate t^{40} , by which the local current is made to pass through a contact-bar M^7 and a contact-plate M^8 , which are joined when a transmitting-lever, as L' , is depressed, as will be hereinafter more fully described. The local current from battery P' now flows through wire t' , arm t^2 , plate t' , relay-magnet R^2 , wire t^6 , arm of switch V^8 , contact-plates t^{40} , wire t^{39} , 100 contact-bar M^7 , contact-plate M^8 , wire t^{41} , plate t^{47} , wire t^{48} to supporting-brace D^2 , and thence to contact-plate e^5 , as before described. All the switches of the series V^4 and V^5 are 105 open in transmitting. The current will proceed from plate e^5 through wire t^{47} , plate K^2 , spring K^3 , wire t^8 to magnet A^6 , and thence by wires t^9 and t^{10} to battery P' in the manner described in the process for receiving. Magnet A^6 will be energized and will draw arm 110 A' and bar F^4 forward, as before, until the contact-brush e^4 passes the plate e^6 and until block K^4 strikes spring K^3 and drives it from contact with plate K^2 , thus breaking the current energizing magnet A^6 . By the recoil of 115 arms A' and A^2 , before described, contact point a' will immediately be thrown against plate a^2 and out of contact with plate a^3 , thus entirely excluding the current from the former magnet A^6 . Arm A^2 will continue its 120 return movement after point a' has reached plate a^2 , the latter being pushed onward by 125 130

said point a' until said plate a^3 strikes the end of the contact stop-pin B^3 , which will arrest the further progress of arm A^2 .

The provisional path from plate a^2 , via plate a^9 , wire t^6 , bars $L^{13} L^{14}$, wires t^6 and t^4 , will admit the current to the second conducting-brace D^2 of the series the instant point a' strikes plate a^3 in all cases where said provisional path is closed by means of the presence of a conducting-plate L^{35} , on the transmitting-lever L' depressed, having contact with the respective pair of conducting-bars $L^{13} L^{14}$, as before mentioned; but in the cases where such conducting-plate L^{35} is lacking to join a pair of said conducting-bars $L^{13} L^{14}$ electrically when the corresponding transmitting-lever is depressed the current cannot reach the next brace D^2 until arm A^2 has completed its return movement and plate a^2 is brought in contact with the stop-screw B^3 , which has contact with said brace D^2 . From the second supporting-brace D^2 the current will reach the originating-battery through the second magnet A^6 in the manner described in connection with the process of receiving impulses, and the break in the local current will end.

In the first of the above cases there will be a very slight break in the local current merely while point a' is passing from plate a^3 to a^2 , while in the latter cases there will be a relatively long one. These impulses and breaks will be imparted to the main line by means of the relay R^2 and will tend to actuate all instruments on the line that are arranged in the manner described for receiving impulses. The arrangement of the various switches and other parts involved in the interchangeable use of this portion of the device is shown diagrammatically in Fig. 10, where the adaptation of an instrument for use in transmitting impulses is shown at the left of the figure and the adaptation of another instrument for use in receiving impulses at a different station is shown at the right.

The transmitting-keyboard consists of a series of levers L' , of insulating material, mounted pivotally upon a shaft which is supported by standards L^2 , attached to any suitable base L^3 . Levers L' are held normally upward by means of a series of springs L^5 and are each provided with a press-button L^4 , bearing some designated letter or character. The upward motion of each of the levers L' is limited by a cross-bar L^6 , mounted above their free ends.

Running transversely beneath the forward portions of levers L' are a series of bars $L^{13} L^{14}$, of conducting material, arranged in pairs and mounted on vertical rods L^{15} , rising from the base L^3 of the keyboard. These bars are held normally upward by spiral springs surrounding rods L^{15} , and their upward movement is limited by nuts screwed to the tops of rods L^{15} . The number of pairs of bars in the series should equal the number of pairs of magnets A^6 used. A series of small con-

ducting-plates L^{35} are attached to the lower margins of the key-levers L' in such a position that when any key-lever is depressed each plate L^{35} will strike the upper margins of a pair of bars $L^{13} L^{14}$ and will join them electrically. The members of each pair of bars $L^{13} L^{14}$ in the series are joined, respectively, by a conducting-wire t^6 to the contact-points of one of the switches V^5 , before described. Two levers M^3 , one on either side of the keyboard, are pivoted to a transverse rod M' , mounted on supports M^2 , and are held normally upward by a spring M^4 beneath. A contact-plate M^5 , attached to one of the levers M^3 , is held normally against a contact-pin M^6 , depending from any suitable support, by the tension of said spring M^4 . A cross-bar M^7 , of conducting material, attached to the ends of levers M^3 , extends beneath the levers L' in such a position that the depression of any lever L' will strike it and carry it downward till it strikes a contact-pin M^8 , mounted on an arm attached to standard M^2 . By this arrangement the depression of any key-lever L' will break the contact between plate M^5 and contact-pin M^6 and will cause a contact of cross-bar M^7 with contact-pin M^8 , which latter are joined, respectively, by conducting-wires $t^{39} t^{41}$ to the contact-plates $t^{40} t^{47}$ of switch V^8 , and thus by this contact a provisional path will be formed for the local current around said switch V^8 , as before described.

The effect of the contact of one of the conducting-plates L^{35} with a pair of the conducting-bars $L^{13} L^{14}$ is, as has been shown, to produce a minimum break in the local current by admitting it immediately from a contact-plate a^3 to a magnet A^6 , and by consequence in the main current also, while the absence of any plate L^{35} tends to cause a longer break in these currents.

By omitting one or more of the plates L^{35} from each of the key-levers L' except one and by varying the positions of those used the order of the long and short impulses may be varied for each of said key-levers, as will readily appear, the number of possible variations having a fixed relation to the number of pairs of conducting-bars $L^{13} L^{14}$ in the series.

Another method of imparting long and short breaks to the main current is shown in Figs. 6 and 7. For this process a bent lever L^7 is placed beneath the forward ends of the key-levers L' and pivoted to standards $L^8 L^9$. To a vertical extension L^{10} of one end of bar L^7 is attached a bar L^{11} , which is drawn by a retracting-spring L^{15} , causing an upward tendency of the bar L^7 toward the key-levers L' . At a point L^{18} on bar L^{11} is pivoted the end of a contact-lever L^{16} , which is fulcrumed to a standard L^{17} . Lever L^{16} bears a contact-brush L^{23} , which is adapted to sweep over a segment L^{21} of conducting material when lever L^{16} is actuated. This will evidently occur by the depression of any key-lever L' in the series.

From the inner margin of segment L^{21} are cut sections of uniform width and at uniform

intervals, corresponding in number to the pairs of conducting-bars L¹³ L¹⁴. The gaps or slots thus made in segment L²¹ are partially filled by contact-plates L²², the remaining unfilled portion of each gap being chiefly on one side of these plates. Each of the plates L²² is electrically connected by wires t³⁴ with one of the conducting-bars L¹³, while each of the bars L¹⁴ is similarly connected with the bars L¹⁴.

10 Segment L²¹, from which the plates L²² are normally insulated. A movable segment L¹⁹ of conducting material is pivoted also at L¹⁷, bearing two shoulders L²⁴ L²⁵, against which the end of lever L¹⁶ is adapted to strike when actuated as described. Segment L¹⁹ is held normally by lever L¹⁶ against a contact-plate L²⁰, which has electrical connection with segment L²¹, but is driven from its contact therewith by the striking of lever L¹⁶ against shoulder L²⁴ when said lever L¹⁶ reaches the end of its forward movement. Segment L¹⁹ and lever L¹⁶ are insulated from each other at the pivot L¹⁷ and are connected with the main line in opposite directions. When segment L¹⁹ is in contact with plate L²⁰ and brush L²³ is in contact with segment L²¹, the main line will be continuous through segment L¹⁹, plate L²⁰, segment L²¹, brush L²³, and lever L¹⁶. It will also be continuous when brush L²³ is in contact with a plate L²², provided the conducting-bar L¹³, to which that plate is joined, is electrically connected with its corresponding bar L¹⁴ by means of one of the plates L³⁵, as before described. In this latter case there would be but a slight break in the main current as the brush L²³ passed over the narrow space between the plate L²² and segment L²¹, while in cases where the plate L²² is not in electrical connection with segment L²¹ by means of such plate L³⁵ joining the corresponding conducting-bars L¹³ L¹⁴ the current will be broken while the brush L²³ is passing over the entire gap in segment L²¹ containing the plate L²² designated. Thus by the depression of a key-lever carrying downward bar L⁷ lever L¹⁶ will be actuated, carrying brush L²³ over segment L²¹ and each of the small contact-plates L²², with the result of producing a short break in the current when a plate L²² is crossed having electrical connection with segment L²¹, and a longer break when a plate L²² is crossed having no such connection, these variations depending on the presence or absence of the plates L³⁵ on the key-lever depressed the same as in the process first described. At the limit of its advance movement lever L¹⁶ will strike shoulder L²⁴ of the segment L¹⁹, driving the segment from its contact with plate L²⁰, thus causing an interruption of the main current while lever L¹⁶ is being restored to its normal position by action of spring L¹².

The portion of the mechanism required exclusively at the receiving-station includes a second local battery P², the contact-springs G³, and contact-plates e² e³, before described, the signals or other devices to be operated,

and certain related parts which will now be described.

The first of the series of sliding blocks F' is provided with a contact-brush b' similar to the brushes e⁴, attached to block F², before described. This brush rests normally on a contact-plate b², and is adapted to be carried with the movement of block F' to a second contact-plate b³.

Two commutator-brushes d⁷ d⁸ are attached to the yokes d³ d⁴, respectively, resting normally on false plates d⁹ d¹⁰ and adapted to be drawn forward in connection with blocks F' F² and yokes d³ d⁴ to rest on contact-plates d¹¹ d¹², respectively, and to be returned to plates d⁹ d¹⁰ by the action of magnets E' and E². Plate b² is connected by wire t²³ to the arm of a switch V⁹, Fig. 9, one contact-plate t⁴² of which is connected by wire t⁴⁴ with contact-plate M⁵ of the keyboard, the other contact-plate t⁴⁶ being connected by wire t⁴⁵ with the contact-pin M⁶, before described, and by wire t²⁴ with plate d¹². By this means there is direct electrical connection made between plates b² and d¹² when the arm of switch V⁹ rests on contact-plate t⁴⁶, and when it rests on plate t⁴² the connection may be continued through wires t⁴⁴ t⁴⁵ when plate M⁵ and pin M⁶ of the transmitting mechanism are in contact—i. e., when no key-lever is depressed. A special sliding block F⁵ is actuated in connection with the last blocks F' F³ of the series, but so as to be restored to its normal position by the return of the corresponding head F³ instead of by the cross-lever H³, which restores said blocks F' F².

To block F⁵ is attached a contact-brush e⁷, resting normally on a false plate and adapted to be carried by the movement of block F⁵ to contact with a conducting-plate e⁸, remaining in contact therewith only while the corresponding magnet A⁶ is energized and the head F³ is actuated.

When the first magnet A⁶ of the series is energized and the first blocks F' F² and connected parts are actuated, brush b' and e⁴ will be carried to contact-plates b³ and e⁶, respectively, and brushes d⁷ d⁸ will be carried to contact with plates d¹¹ d¹², respectively. A path will then be opened for the current from battery P² by wire t¹⁵, first supporting brace D' in the series, brush b', plate b³, wire t¹⁶, to the first spring G³ of the series.

One of the first plates e² e³ of the series is connected by wire t¹⁸ or t¹⁷, respectively, to the second spring G³, one of the second plates e² e³ is similarly connected with the third spring G³, and so on, the last plate e² or e³ being connected with brush e⁷ of block F⁵. If the current be not interrupted between plate b³ and brush e⁷, it will, when the latter is in contact with plate e⁸, proceed thence by wire t¹⁹ to the actuating-magnet of signal T, which it will energize, passing through wire t²⁰ to plate d¹¹ and thence by brush d⁷, wire t²¹, magnet E', and wire t²² to battery P² again, energizing magnet E', which will restore

brush d' , block F' , and brush b' to their normal positions. I have shown that a short interval of break in the main current will cause a spring G^3 to fall on a plate e^2 , and a longer break will cause it to fall on a plate e^3 , and also that either plate e^2 or e^3 may be connected with the next succeeding spring G^3 . It will plainly appear that any designated order of connecting these plates will require a corresponding order of impulses to carry the local current from battery P^2 through the entire series of plates and actuate the signal T . For instance, let plate e^2 of the third block F' be connected with the next spring G^3 by wire t^{18} , while plates e^3 of the second, fourth, and all succeeding blocks F' are so connected by wires t^{17} . Then if a series of impulses be received in which the second interval of break is short and the first, third, and all succeeding intervals are long the first spring G^3 of the series will drop on plate e^3 , the second on plate e^2 , the third and all succeeding ones on plates e^3 , and thus a path will be opened for the current to signal T , while any other order of intervals would cause the spring G^3 to drop so as to break the path at some point. Thus by using a special arrangement of connections for the plates e^2 e^3 for each station on the line one particular order of impulses will actuate the signal at one station, and only one, which is one of the objects sought to be accomplished by my invention. After magnet E' has been energized and brush b' restored to plate b^2 the current will proceed by wire t^{23} , through the arm of switch V^9 , contact-plate t^{16} , wire t^{24} , contact-plate d^{12} , brush d^8 , wire t^{27} , electromagnet E^2 , wires t^{28} t^{29} , to battery P^2 , energizing magnet E^2 and causing it to restore block F^2 to its normal position. In transmitting it is necessary to prevent the energizing of magnet E^2 till the depressed key-lever L' is restored, breaking the current from battery P' at M^7 M^8 , lest there should be a repetition of the signal transmitted. This is accomplished by throwing the arm of switch V^9 to contact-plate t^{42} , from which the current may proceed by wire t^{44} to plate M^5 and contact-pin M^6 , when the two latter are in contact—*i. e.*, when the key-lever L' is restored to normal position—thence by wire t^{45} , plate t^{46} , and wire t^{24} , as before. This withholds the current from magnet E^2 till the depressed key-lever is released by the operator, thereby preventing a restoration of the first block F^2 to normal position and in consequence a repeated energizing of the magnets A^6 with a single depression of a key-lever.

The mechanism for actuating any one of a series of signals or other devices simultaneously at one or more receiving-stations, which is the second of the described objects of this invention, consists of a series of electromagnets N^2 , Figs. 8 and 5, which, by means of connecting-bars N^3 , impart a slight rotary motion to horizontal shaft N' , suitably mounted on standards inserted in the base beneath. To

each shaft N' is rigidly attached one or more drivers N^4 , of insulating material, which engage a series of movable contact-plates N^{14} 70 by means of slots on the lower margins of the latter. By means of these drivers the plates N^{14} are carried forward and backward by the oscillations of shafts N' . One end of each sliding plate N^{14} in the series rests continually on an initial contact-plate N^5 , while the other end rests on a terminal plate N^{15} and is carried to a second terminal plate N^{16} when actuated by the corresponding driver N^4 .

In the case under consideration each contact-plate e^3 of the series before described is connected by wire t^{17} with the next succeeding contact-spring G^3 , while each of the corresponding plates e^2 is connected, respectively, with the initial contact-plates N^5 by 85 wires t^{18} . Thus when a spring G^3 falls upon a plate e^3 the current is carried directly to the next spring G^3 , but when a spring G^3 falls on a plate e^2 the current will be carried to the corresponding initial plate N^5 , and 90 thence by sliding plate N^{14} to the first terminal plate N^{15} , from which it will proceed by wire t^{29} , magnet N^2 , wires t^{30} t^{31} to battery P^2 . This will energize magnet N^2 and cause it to actuate driver N^4 and carry sliding plate 95 N^{14} forward to the second terminal plate N^{16} , by which means the current will be interrupted through magnet N^2 and carried by wires t^{32} and t^{17} to the next contact-spring 100 G^3 . By this means in any case when a spring 105 G^3 falls on a plate e^2 the corresponding magnet N^2 will be energized and its connected parts actuated, and in every case the current will finally reach the brush e^7 of block F^5 . A second series of sliding plates N^{17} similar 110 to plates N^{14} and similarly actuated are arranged in the following order—viz., one sliding plate for the first shaft N' in the series, two for the second, four for the third, and so on, each shaft N' having double the number 115 of plates of the preceding one. Each of these sliding plates N^{17} rests upon an initial contact-plate N^{18} and is adapted to be carried forward to rest upon the initial contact-plate N^{18} of a sliding plate N^{17} corresponding to 120 the next shaft N' of the series. Each terminal plate is electrically joined to an initial plate N^{18} of the next advanced set of such plates, to which no sliding plate N^{17} is carried from the previous set. All the sliding 125 plates of any set are actuated simultaneously when the shaft N' corresponding thereto is oscillated. It will readily be discovered that for any position of the sliding plates N^{17} there is one path from the first initial plate 130 N^{18} to the last set of plates N^{18} , and only one, and for every variation made in the arrangement of those plates by the operations of one or more of the shafts N' a different path is opened, the number of the final emerging 135 paths indicated by the wires t^{33} being equal to that power of two denoted by the number of shafts N' in the series.

In each of the emerging paths t^{33} is located

- an electromagnet N³⁰, designed to actuate a signal or any special device. When brush e⁷ is carried into contact with plate e⁸, the current proceeds by wire f¹⁹ to the first initial 5 plate N¹⁸, thence by one of the paths described through plates N¹⁷ N¹⁸ N¹⁹ to one of the final plates N¹⁸, and from that by the corresponding wire f³³ and magnet N³⁰ to wire f²⁰, whence it reaches battery P² in the manner 10 already described in connection with the actuating of single signals. This energizes the magnet N³⁰ in the particular path opened and causes it to actuate mechanism for printing a character or producing a signal or other 15 special effect, as desired. The corresponding magnet N³⁰ will be energized at each receiving-station on the line and the corresponding effect produced at each of such stations simultaneously.
- 20 Shafts N' are restored to normal position by means of a bar N⁷, which is actuated longitudinally in connection with the mechanism operated by the magnets N³⁰ in a manner not here shown.
- 25 Pins N⁹, inserted on bar N⁷, are brought against arms N⁶, which are attached to shaft N', and restore said shafts to their normal position.
- Having thus described my invention, what 30 I claim as new is—
1. A series of levers actuated by electromagnets and provided with contact-points, a laterally-movable block having contact-plates in proximity to the contact-point of 35 said lever and adapted to alternately connect electrically therewith by the lateral movement of said block, blocks slidable upon said levers and having spring-contact plates attached thereto, a series of slidable blocks 40 upon fixed guides having contact-plates separated by an inclined stop against which said spring-contact rests, and electrical connections, whereby when said levers are actuated, its contact-points will close a circuit through 45 one of the contact-plates on said laterally-movable blocks, and hold it closed so long as the electric current is maintained through the electromagnets which operate said levers, and the contact-points of said levers be returned 50 to their normal positions into electrical connection with the other contact-plates of said laterally-movable block when the current is broken through said magnets, and whereby also a current shall be thrown 55 through a second magnet to close a circuit through the contact-plates upon said slidable blocks when they are brought into predetermined positions before the contact-points upon said levers are returned to their normal 60 positions, substantially as and for the purpose set forth.
  2. In an electric-signal distributor, a series of bent levers actuated by electromagnets and retracting-springs and with sliding bars 65 of insulating material actuated in connection with and during the advance movement only of said levers, a series of contact-plates con-
  3. In an electric-signal distributor, a series of levers actuated by electromagnets and retracting-springs, sliding bars of insulating material actuated in connection therewith, contact-plates adapted to divert the electric current energizing said electromagnets, an insulated contact device rigidly attached to 100 said lever and adapted to move between and make contact with two insulated contact-plates attached to an oscillatable block, one of said attached plates having a provisional 105 electrical connection with the next advanced electromagnet of the series, a contact-stop having electrical contact with said attached plate when said attached plate is in normal 110 position, and having constant electrical contact with said advance magnet, a block of insulating material carrying a contact-plate, a contact device mounted loosely upon the free 115 ends of said levers and adapted when said lever is actuated to move in a direction approximately at right angles to the direction of movement of the next advance sliding bar of the series, and two contact-plates mounted 120 rigidly upon the lateral surface of each of said sliding bars, except the first of the series, 125 said contact-plates being separated from each other by a narrow insulating projection and said sliding bar being so placed normally that said contact device of the preceding lever shall rest normally against the first of said 130 contact-plates and immediately in front of the insulating projection being engaged thereby; whereby when the current is carried to any of the actuating-magnets of the series

from the contact device of the last preceding lever of the series when said lever begins its return movement toward its normal position, said actuating-magnet will cause said 5 sliding bar to advance before said contact device upon said insulating-block has reached its normal position beneath said insulating projection and in contact with said first contact-plate attached to said sliding bar, with 10 the result of bringing said contact device at its full return to its normal position into contact with the second of said contact-plates attached to said sliding bar to cause said contact device to rest optionally upon the first 15 or second of the contact-plates upon said sliding bar according as the magnet actuating said sliding bar is energized at the beginning or at the close of the return movement of the last preceding lever of the series, and 20 thereby producing a selective path for an electric current through the several contact devices of the series, and the corresponding and alternative contact-plates of the sliding bars, substantially as described and for the 25 purpose set forth.

4. In an electric-signal distributor, a series of bent levers actuated by electromagnets and retracting-springs and with sliding bars of insulating material actuated in connection with 30 and during the advance movement only of said levers, a series of insulating-blocks carrying a contact device and loosely mounted upon the free ends of said levers, a series of restoring-levers actuated in connection with 35 said electrically-actuated levers, whereby the forward movement of each of said electrically-actuated levers shall operate to restore to their normal position both the insulating block mounted thereon, and the next succeeding 40 sliding block of the series, the first sliding bar being restored to its normal position by a special magnet, substantially as described and for the purpose set forth.

5. In an electrical - signal distributor, a 45 mechanism whereby each of a series of primary electric contact-points is brought into contact with either of two corresponding insulated alternate contact-points; a series of adjusting electromagnets connected respectively with the like number of each set of 50 said corresponding contact-points by an electrical conductor, each magnet being adapted when energized to actuate an oscillating bar, a series of movable contact-plates engaged 55 by each of said oscillating bars, each movable contact-plate connecting normally an initial contact-plate with one of two corresponding terminal contact-plates and adapted to be moved by said oscillating bar so as to connect 60 the same initial contact-plate with the second of said corresponding terminal contact-plates, whereby each terminal contact - plate being electrically connected with a respective initial contact-plate of the next succeeding series of 65 movable plates and thus doubling the number of contact-plates in any series over that of the last preceding series, and an elec-

tric current entering the initial contact-plate of the first series may be made to enter either of two initial plates of the second series, any 70 of four initial plates of the third series, any of eight initial plates of the fourth series, and so on in the same ratio for any number of series so erected, with the result of bringing said electric current to any desired one of a 75 series of actuating - electromagnets corresponding to the number of terminal contact-plates in the last or highest of said series of such contact-plates, according to the order in which said adjusting-magnets may be energized, this in turn depending upon the order 80 in which the said primary contact-points may be connected with the corresponding alternate contact-points, and with the further result of energizing such actuating-magnet for 85 the purpose of operating a signal or printing a character, substantially as described and for the purpose set forth.

6. In an electrical distributer, a series of levers actuating magnets and retracting- 90 springs, sliding bars of insulating material actuated in connection therewith, an insulated contact device attached rigidly to each of said levers, and contact-plates each attached to an oscillating block and adapted to 95 make contact with a corresponding contact device when the latter begins its retrograde movement, a keyboard consisting of a series of insulated key-levers held normally upward by springs, said levers having insulated contact-plates so placed that when any key-lever 100 is depressed, each of said key-lever contact-plates electrically joins the two members of a series of pairs of spring-supported contact-plates, one of the members of each pair of 105 said spring-supported contact-plates having electrical connection respectively with one of the said contact-plates attached to an oscillating block, and the other member of each pair of said spring-supported contact-plates 110 having electrical connection with the actuating-magnet next in series above the one by which said attached contact - plate is actuated, whereby any desired combination of 115 said attached contact-plates with their corresponding advanced magnets may be effected by depressing the key-lever having the correspondingly - arranged insulated contact-plates, with the result of energizing each of 120 said advance magnets at the moment the respective preceding electrically-actuated lever begins its return movement, and with the further result of producing a comparatively short 125 interruption of the local electric current energizing said series of actuating-magnets, said interruptions being communicated by a relay with a main line, whereby similarly-constructed instruments at distinct points on said main line may be caused to produce synchronously 130 the same movements as the corresponding parts of the transmitting instrument, substantially as described and for the purpose set forth.

7. In an electrical distributor, a segmental

contact-plate connected with said main line on one side of a switch, and having radiating slots partially filled with insulated contact-plates, a lever bearing a commutator connected on the opposite side of said switch with the main line, and adapted to move over said segmental contact-plate and said radiating slots and insulated contact-plates, a series of spring-supported key-levers having insulated contact-plates adapted when the key-lever is depressed to electrically join the two members of a series of pairs of spring-supported contact-plates, one member of each of such pairs of contact-plates being electrically connected with said segmental contact-plate, and the other member being connected respectively with one of said contact-plates in the slots of said segment, a rod beneath the ends of said key-levers and connected to said commutator-lever, whereby when any of said key-levers are depressed said commutator-lever will be carried across said slots and the contact-plates therein, and the contact-plates of said key-levers will join said spring-sup-

ported contact-plates, with the result that 25 when said commutator crosses a slot in said segmental plate containing a contact-plate having electrical connection with the segment through said spring-supported contact-plates and said key-lever contact-plates, the interruption of the main current will be a short one, but when said commutator crosses a slot having a contact-plate having no electrical connection with the main segmental plate, the interruption will be more protracted, 30 35 whereby the order of longer or shorter interruptions will vary according to the arrangement of contact-plates upon the different key-levers depressed, substantially as described and for the purpose set forth.

In testimony whereof I have hereunto set my hand in the presence of two subscribing witnesses.
